UNITED STATES PATENT OFFICE.

CHARLES NEVATT, OF GLASGOW, SCOTLAND.

ROLLER WINDOW-BLIND FITTING.

Application filed June 11, 1924. Serial No. 719,410.

To all whom it may concern:

Be it known that I, CHARLES NEVATT, of 23 Darnley Gardens, Pollokshields, Glasgow, Scotland, a British subject, have invented 5
certain new and useful Improvements in or Relating to Roller Window-Blind Fittings, of which the following is a specification.

The present invention relates to the fittings for window blind rollers and more 10 particularly to those used for solid rollers.

Solid blind rollers, as at present constructed, are usually provided with a cap or disc 15 screwed to each end thereof, the cap or disc at the one end of the roller carrying merely a pivot pin formed integral with it and adapted to be located in a bearing carried by a bracket mounted on the window frame or on a lath secured thereto, while the cap or disc at the other end of the roller carries 20 a similar pivot pin, whereon is mounted a ratchet wheel adapted to be held by a detent on the adjacent supporting bracket.

In assembling the fittings on the roller these caps or discs have each to be secured 25 to an end of the roller by three or four screw-nails, an operation involving time and trouble. Further, as the fittings are made integral with the caps or discs, they have to be made in various sizes corresponding to 30 rollers of various diameters so that a great many different fittings have to be kept in stock.

The object of the present invention is to 35 provide end-fittings for blind rollers in which the only part that requires to be changed with variations in the diameter of the roller is the cap or disc, hereafter called the endplate, the remaining parts being of one standard size adapted to be associated 40 with the said end-plates of varying size, whereby the number of parts required for a complete range of blind rollers may be reduced, and, furthermore, to provide an end-fitting which will be more conveniently and 45 expeditiously assembled and secured than hitherto.

As the end fittings apart from the end-plates, comprise a spike they will be herein-after referred to as "spike-fittings."

Convenient constructions of the invention 50 will now be described by way of example and with reference to the accompanying drawings.

On the drawings:—

Fig. 1 is a side view partly sectioned, 55 showing one form of a blind roller ratchet spike-fitting.

Fig. 1^a is an end view thereof looking from the point of the spike and with the roller removed. 60

Fig. 1^b is a view of the end-plate to be associated with the spike-fitting.

Fig. 2 is a view similar to Fig. 1 showing a modified form of spike-fitting. 65

Fig. 2^a is an end view of the spike-fitting;

Fig. 2^b is a view of the accompanying end-plate;

Fig. 3 is a side view showing a second modified form of spike fitting. 70

Fig. 3^a is an end view of the same; 70

Fig. 3^b represents the associated end-plate;

Fig. 4 is a side view of a spike-fitting for the cord at the opposite end of the roller; 75

Fig. 4^b is an end view thereof.

Considering the first form of the invention as illustrated by Figs. 1, 1^a and 1^b, the ratchet spike-fitting comprises a spike 1 having an end-plate retaining boss 2, and a pivot or journal 3 for the roller; a ratchet wheel 4 loosely mounted on the portion 3 of the spike and held frictionally in place by spring washers 5, 5; and a collar 7 pinned to the part 3 and retaining the spring washers and ratchet wheel in place on the fitting. The washers shown have radiating arms 6, one of the washers being disposed between the boss 2 and the wheel 4, and the other between the wheel 4 and the collar 7. When it is desired to have a cord at this 90 end of the roller for raising the blind the boss 2 may be extended axially to provide a drum therefor.

The fitting is, on the right hand side of the boss 2, provided with a round driving portion having a point 8 at its extremity and between the driving portion and the boss 2 it has a substantially square portion at 9, and which is gradually expanded on two sides until at the part 10 next the boss 2 it 100 is substantially rectangular having two sides approximately double the width of the other two sides. These broad sides after the spike-fitting has been driven into the roller 13 give a large bearing surface adapted to prevent relative rotation of the spike-fitting and the roller under the action of the blind operating means. 105

The end-plate 11 for this spike-fitting is a separate disc having an inwardly projecting flange 12 to encircle the end of the blind roller 13. At its centre this disc is provided with an aperture 11^a of a shape to fit the rectangular portion 10 of the spike. A part of the roller 13 is shown, in section, merely to indicate the relative positions of the parts.

Figs. 2, 2^a, and 2^b illustrate a modified construction of the invention wherein the ratchet wheel spike-fitting is provided with a round spike 1 having side flutes or grooves 14 in its driving portion to prevent its turning in the roller, this being instead of the rectangular portion 10 aforesaid; and for the same purpose, projections 21, 21, may be made on the boss, these projections passing through holes 22, 22, in the end-plate 20 and entering the roller when the spike-fitting is driven into place. The end plate has a flange 12 and a circular aperture 11^b. The remaining parts are precisely similar to those above described.

A further modification of the ratchet wheel spike-fitting is shown in Figs. 3, 3^a and 3^b in which the spike 1 has two parallel flat faces 15, 15, formed on its driving portion with the object of increasing resistance to relative rotation of roller and pin; projections 21 may also be used. In this case the end plate has a flange 12 and an aperture 11^c of the shape shown in Fig. 3^b. In some cases I may use only a single spring washer 5.

In practice the end-plate 11 is driven on to the end of the roller 13, and thereafter the spike-fitting 1 with its ratchet wheel 4 and springs 5 affixed, is driven so that the driving portion 1 enters into the roller end through the aperture 11^a, 11^b, 11^c, in the end-plate. It will be obvious no screws are required as the spike is firmly secured in the wood and, by its boss 2, holds the end-plate in position.

The other end of the roller is or may be provided with an end plate similar to that already described. The corresponding spike-fitting for this end is made as shown in Figs. 4 and 4^b. It has a pointed driving portion 16, a cord drum or part 17 with an aperture 18 therein to receive the end of the cord, a disc 19 secured at one end of the drum to act as a guide to the cord and a journal portion 20 to be received in a bearing in the supporting bracket. The driving portion of the spike may be formed in any one of the three ways described and illustrated with reference to Figs. 1 to 3^b and it may have projections 21, 21. If no cord is to be attached at this end, the driving portion of the spike may be merely of circular section

having a boss to hold the end-plate in position.

It will be appreciated that with end-fittings of this sort, the only parts that require to be altered for different sizes of blind rollers are the end-plates, all the other parts remaining exactly the same for every size. This naturally is a great convenience, considerably cheapens manufacture, requires the stocking of a much smaller number of parts for a complete range of blind rollers, and greatly facilitates the operation of fitting up the roller for use.

The ratchet spike fittings complete with ratchet and springs would be supplied ready for being secured to any blind roller and the cord spike-fittings would also be supplied in the same way. The end plates would be supplied separately and would, of course, be of different diameters to suit different rollers.

The spike fittings are driven into the roller by simply striking the portions 3 or 20, as the case may be, with a hammer.

Having now fully described my invention what I claim and desire to secure by Letters Patent is:

1. End fittings for a solid window blind roller, each comprising a disc having a peripheral flange to fit the normal end of the roller, and a spike member passed through the said disc into the roller and adapted to prevent rotation of the disc, said member comprising at its outer end an enlarged boss, at its inner end a driving portion, and formed between the boss and driving portion to present a trunk of rectangular section which from the part next the driving portion is gradually expanded to the part next the boss.

2. End fittings for a solid window blind roller, each comprising a disc having a peripheral flange formed to fit the normal end of the roller, a spike member passed through the disc into the roller and adapted to prevent rotation of the disc, and means to prevent rotation of the spike in the roller, one end fitting having a cord drum integral with the spike, a disc at the end of said drum, and a pivot bearing beyond the disc, the other end fitting having a plurality of collars arranged in spaced relation on the spike beyond the disc, a ratchet wheel loosely mounted on the spike between the collars, and a plurality of spring members supported on the spike and bearing between the respective sides of the ratchet wheel and the adjacent collar.

In testimony whereof I affix my signature.

CHARLES NEVATT.
